[57] CLAIM

The ornamental design adjustable flexible holder for a bucket, as shown and described.

DESCRIPTION

FIG. 1 is a front perspective view of one embodiment of an adjustable flexible holder for a bucket, showing my new design;

FIG. 2 is a front elevation thereof;

FIG. 3 is a rear elevation thereof;

FIG. 4 is an elevation of one side thereof;

FIG. 5 is an elevation of the other side thereof;

FIG. 6 is a top plan thereof, the bottom plan being a mirror image;

FIG. 7 is a front elevation thereof with the looped portion shown in opened position;

FIG. 8 is a rear elevation thereof showing strips of hook and loop velcro on the horizontal webbing;

FIG. 9 is a front perspective view of a second embodiment thereof;

FIG. 10 is a front elevation thereof;

FIG. 11 is a rear elevation thereof;

FIG. 12 is an elevation of one side thereof;

FIG. 13 is an elevation of the other side thereof;

FIG. 14 is a top plan thereof, the bottom plan being a mirror image;

FIG. 15 is a front elevation thereof with the looped portions shown in opened position; and,

FIG. 16 is a rear elevation thereof.

The crosshatching, which is partially shown for ease of illustration, represents a conventional material and is understood to repeat throughout the areas indicated.
